CLAIM

The ornamental design for candy, as shown and described.

DESCRIPTION

1. Candy

1.1: Front perspective

1.2: Front elevation

1.3: Back elevation

1.4: Right-side elevation

1.5: Left-side elevation

1.6: Top plan

1.7: Bottom plan

(Continued)

The dashed broken lines depict portions of the candy that form no part of the claimed design. The dot-dashed broken lines represent boundaries of the claimed candy and form no part of the claimed design.

1 Claim, 7 Drawing Sheets
